UNITED STATES PATENT OFFICE.

JAMES C. MILES, OF BLOOMINGTON, ILLINOIS.

HOT-AIR HEATING APPARATUS.

Application filed April 9, 1923. Serial No. 630,740.

This invention relates to apparatus used in hot air heating systems and more particularly refers to an apparatus used in a system such as is shown and described in 5 Patent No. 1,508,813 issued to me September 16, 1924.

Briefly, the apparatus illustrated in Patent No. 1,508,813 embodies a fan and a damper associated therewith which are arranged to be positioned adjacent the inlet to the heating chamber of a furnace. The damper is arranged to be open when the fan is stopped, and to be closed by the action of air pressure within the chamber 15 when the fan is in operation.

One of the objects of this invention is the provision of means for insuring opening of the damper when the fan is shut off. Another object is the provision of means 20 whereby the damper is closed when the fan is set in operation so as to prevent the passage of air through the passageway across which the damper extends.

The means for accomplishing the above objects will be hereinafter fully described in connection with the accompanying drawings and the essential features will be summarized in the claims.

In the drawings, Fig. 1 is a side elevation 30 of a furnace showing the conduit leading thereto and illustrating my invention within the conduit adjacent the heating chamber of the furnace; Fig. 2 is a rear elevation of a unit embodying my invention; Figs. 3 35 and 4 are sections taken on the correspondingly numbered lines respectively in Fig. 2; Fig. 5 is a modified form of damper showing the application of my invention when the normal inlet to the furnace is separate from the inlet controlled by the 40 fan; while Figs. 6 and 7 are horizontal and vertical sections respectively through the damper illustrated in Fig. 5.

In Fig. 1, I have shown the heating chamber of a hot air furnace at 10, with an inlet housing 11, and an inlet conduit 12. Disposed across the inlet opening and adjacent the casing 11, I have illustrated a frame indicated generally at 13 which is provided 45 with a central passage 14 and with preferably two side passageways 15 and 16 respectively. Adjacent the central passage, I have shown a fan 17 which is operated by a motor indicated generally at 18. Disposed 50 adjacent the openings 15 and 16, I have shown dampers 19 and 20 respectively which

dampers are so mounted that they are automatically moved to open position when the fan is stopped, and pneumatically moved to closed position when the fan is set in operation. Thus I provide sufficient area for the admission of air when the fan is stopped, to prevent overheating or burning out of the furnace.

To effect an automatic operation of the 65 dampers consequent upon starting and stopping of the fan, the axes of the shafts 21 and 22 on which the respective dampers are supported incline toward the furnace as shown in Fig. 3. Moreover, each shaft extends lengthwise of the damper and is positioned to one side of a line passing through the midportion thereof. Consequently, each damper has more weight on one side of the axis than on the opposite side, wherefore the 70 inclination of the shaft causes the heavier side of the damper to incline inwardly as shown by the broken lines 19^a and 20^a respectively in Fig. 4. Conversely, when the fan is in operation and the air pressure in 75 the chamber is greater than that in the air conduit 12, then since the area on the portion of each damper which extends toward the furnace is greater than that extending away from the furnace, the dampers are 80 pneumatically closed and are maintained in closed position so long as the fan is in operation.

With the apparatus heretofore described, the fan and dampers are arranged in a unitary structure which may be placed adjacent the inlet conduit of the hot air furnace. For installations wherein the usual inlet to the furnace is not satisfactory for permitting the use of the combined fan and 90 damper unit, I may obtain the same desired result by utilizing one inlet for the fan and another for the damper as illustrated particularly in Fig. 5.

In this figure, the heating chamber casing 100 30 is provided with a normal air conduit 31 and a fan inlet conduit 32. These conduits may receive air from different parts of the building in which the furnace is placed. Within the conduit 31, I have shown a 105 frame 33 in which a shaft 34 carrying a damper 35 is supported. This shaft as heretofore described is placed to one side of the mid-portion of the damper and is so supported within the frame that the top 110 thereof inclines toward the furnace. Normally then, that is, in the gravity system,

the damper is inclined toward the furnace as shown in Fig. 5 and in broken lines 35° in Fig. 6, but when the fan is in operation, the damper is adapted to be pneumatically closed by the pressure acting on the larger area, as heretofore explained.

In view of the foregoing description, it will be seen that my invention provides a damper which is automatically opened 10 when the air impelling means is shut off, but which is pneumatically closed when the air impelling means is set in operation. This is particularly advantageous in that 15 automatic opening of the damper is effected as soon as the motor which operates the fan is stopped, wherefore sufficient air is admitted into the furnace to prevent overheating under the gravity system.

I claim:

- 20 1. In combination, a heating chamber having an air inlet, a fan for forcing air through the inlet, a damper mounted on an upright inclined pivot adjacent the inlet, said pivot being so positioned relatively to the damper that the normal action of gravity tends to open the damper when the fan is stopped, and permits closing of the damper when the fan is in operation.
- 25 2. In combination, a heating chamber having an inlet, a fan for forcing air through the inlet, a damper adapted for controlling the flow of air in the chamber, said damper being supported on an upright inclined pivot on one side of the midportion thereof whereby the action of gravity normally tends to open the damper when the fan is stopped, but permits pneumatic closing of the damper when the fan is in operation.
- 30 3. In a heating apparatus, the combination with a heating chamber having an air inlet, of a frame having two openings therein and positioned across the inlet, a fan occupying one of the openings, a damper occupying the other of said openings, said damper being pivotally mounted on the frame in such manner that the top of the pivotal connection extends toward the

chamber wherefore the action of gravity tends to open the damper when the fan is stopped, and permits closing of the damper when the fan is in operation.

4. In a heating apparatus, the combination with a heating chamber having an air inlet, of a frame positioned across the inlet and having means for supporting a shaft in upright position, one end of said shaft being nearer the chamber than the opposite end thereof, a fan mounted in the frame on one side of the shaft, and a damper carried by the shaft in such manner that the action of gravity normally urges the damper to open position while the fan is stopped, and permits closing of the damper by pneumatic pressure when the fan is in operation.

5. In a heating apparatus, the combination of a heating chamber having an air inlet, of a frame positioned across the inlet, said frame having three openings therein, a fan positioned adjacent the central opening, dampers pivotally mounted in upright position in the end openings, the pivotal connection for each damper being inclined at the top toward the chamber and also being on the outer sides of the mid-portion of the damper openings, whereby the action of gravity normally tends to hold the dampers open when the fan is stopped, and to close the dampers when the fan is in operation.

6. In combination, a heating chamber having an inlet, a fan for forcing air through the inlet, a damper adapted for controlling the flow of air in the chamber, said damper being supported on an upright inclined pivot on one side of the center of gravity thereof so that the action of gravity normally tends to open the damper when the fan is stopped, but permits pneumatic closing of the damper when the fan is in operation.

In testimony whereof, I hereunto affix my signature.

JAMES C. MILES.
